UNITED STATES PATENT OFFICE.

WILLIAM GRANT IVES AND MARTIN A. IVES, OF CHICAGO, ILLINOIS.

SECTIONAL GARBAGE AND REFUSE RECEPTACLE.

Application filed April 29, 1922. Serial No. 557,486.

This invention relates to improvements in knock-down garbage and refuse receptacles, heretofore largely consisting of portable sheet metal boxes and cans, provided with 5 either removable or hinged covers, and which, because of their portability, are kept inside of dwelling houses and apartment buildings, and which, at best, are unsatisfactory and difficult of cleansing of liquids retained 10 therein and matter adhering to the sides and bottom thereof, making their use accordingly objectionable, especially when, for any reason, they are not emptied at least once every day.

15 The prime object of this invention is a garbage and refuse receptacle, which is non-portable and unfitted for indoor use, constructed of a material, preferably reinforced concrete, throughout, with the exception of 20 the necessary doors for closing the openings necessary for the introduction and removal of the garbage from the box.

25 A further object of our invention is a refuse receptacle, the bottom, sides and top of which are separately constructed of reinforced concrete or cement, adapted to be assembled and secured together to form the receptacle, molded to form openings suitable for introducing and removing the contents therefrom.

30 Another object of this invention is a garbage receptacle, constructed in standardized sections, for accordingly duplicating as many other such boxes as may be desired, and also as a means for their substitution for any injured corresponding section necessary for 35 the repair of the used receptacle, and without substantial injury to any of its uninjured sections.

40 A further object of this invention is to have the bottom of such garbage box so formed as to facilitate the removal of garbage in its entirety therefrom by means of a shovel or flat-tined fork, and that the drainage of the liquid from the garbage will be concentrated at such a point on the bottom as to 45 facilitate the convenience of the removal of such liquid, and materially reduce to a minimum its liability to freeze, or, when frozen, to injure the box.

50 A still further object is to provide closure attachments which are readily replaceable without injury to the structure.

55 With these ends in view, our invention finds embodiment in certain features of novelty in the construction, combination and arrangement of parts, by which the said objects and

certain other objects are attained, all as hereinafter fully described with reference to the accompanying drawings and more particularly pointed out in the claim.

In said drawings,—

Fig. 1 is a vertical transverse section taken on the line 1, 1, of Fig. 2, of a garbage box constructed in sections, formed of reinforced concrete or cement, in which my invention 65 finds embodiment.

Fig. 2 is a top plan view of the garbage box, partly in section; and

Fig. 3 is a front elevation thereof, partly in section, showing the door closing the opening through which the garbage and other refuse are removed from the box.

Figure 4 is a fragmentary view in elevation of a constituent element of the structure showing the manner in which the closure attachments are associated therewith.

Similar characters of reference indicate the same parts in the several figures of the drawing.

As shown in the drawings, the garbage box 80 of our invention consists of a number of sections, a section 4 of which forms the bottom, an inclined top section 5, the rear side of the box, integrally connected with which is an inclined top portion 6, the end sections 85 7, 7, each of which is formed of one piece, and with a front side 8, to which is integrally connected another part of the top 9 of the box, the front side 8 terminating at its lower end in a curved portion 9', the purpose of which will hereinafter be described.

The upper surface of the bottom section 4 is concave, as indicated by the line 10 in Fig. 1, for facilitating the removal of garbage 95 from the receptacle by means of a shovel, which bottom is also inclined downwardly from its longitudinal rear edge to form a concavity as indicated at 11, to a point adjacent its longitudinal front edge, whence it inclines upwardly at 12 for thereby providing a sump for collecting liquid drawn from the garbage in the box, and at a point most convenient for its removal therefrom and for preventing the adhering, and particularly the freezing of the garbage to a substantial 100 portion of the surface of the bottom. In other words, the concavity in the bottom of the box provides a means for the expansion outwardly of ice formed therein and renders such expansion negligible in its tendency to 105 exert a force tending to injure and crack the bottom and side walls of the receptacle.

Each of the sections above described is formed and preferably molded from reinforced concrete or cement, and the bottom 4 preferably with an annular recess 13, adjacent to its rear edge, which recess extends across both ends of the bottom to respectively form a seat and an abutment for the rear side 5 and both end sections 7 of the box.

The end sections of the receptacle also have 10 molded therein perforations 14, at intervals of their height, located next the inner walls of the front and rear side sections thereof, through which pass rods 15, provided at one end with heads 16 and at the other ends with 15 screwthreads 17, on which work nuts 18. The rods 15 obviously, therefore, aid greatly in supporting the front side 8 and in maintaining the rear side 5 in substantially vertical position.

20 In short, the rods 15 connect the end sections of the receptacle at such intervals that the tightening of the nuts 18 thereon operates to clamp the end sections tightly against the ends of the side sections, as clearly indicated in Fig. 3.

The two parts 6 and 9 are spaced apart to provide, extending lengthwise of the receptacle, an opening through which to introduce garbage into the receptacle, adapted 30 to be closed by a downwardly inclined door 19 which is secured by a hinge, the straps 20, 20 of the hinge being riveted to the door and provided with eyes 21, pivoted on a rod 22, surrounded by eyes 23, 23, formed integral with the headed bolts 24, 24, passing through perforations molded in the section 9, thereby being readily removable without injury to the section in the event breakage of the eyes occur.

40 The curved end 9 of the side section 8 is spaced from the bottom 4 a sufficient distance to provide an opening extending lengthwise of the receptacle for the removal of the garbage contained therein, by any suitable 45 means, preferably by means of a shovel, which opening is closed by a door 25, hinged at one end by a strap 26, riveted thereto, provided with eyes 27, pivoted on a rod 28, passing through eye-bolts 29 in the edges of the 50 ends of the receptacle, either by socketing and cementing the eye bolts, but preferably by imbedding therein, the shanks 29' thereof which are apertured at their ends to receive a pin 30 cast or moulded in the end slabs of 55 the box.

The door 25 is provided at its opposite end with a latch bolt 31 having a handle 31' for engagement with a notched keeper 32, of standard construction, which latch bolt is 60 provided with a pivot 33, at its other end to facilitate pivotal movement thereof. The shank 32' of the keeper is also provided with an aperture to receive a pin 33'.

In practice, the perforations and recesses 65 for the reception of the several eye-bolts and

for the loops, are preferably molded in while casting the respective sections of the receptacles, but it would not be a substantial departure from my invention, although perhaps more expensive, to locate the bolts in 70 the molds so as to fasten in the concrete or cement when being molded.

If desired, the meeting edges of the several sections may have their joints cemented when 75 assembling them, but in practice it is found that this need not be, because of the tightness of their joints in their operative position, and that, in the absence of cement, an injured section may be the more easily removed and a 80 similar section be substituted therefor.

In assembling the several sections for the receptacle of our invention, the bottom is first located in the position it is designed to permanently occupy, followed by erecting thereon the remaining sections for completing the receptacle, and then hinging the doors 19 and 25 in their operative position. In this connection it is again to be noted that the section 6 and the door 19 occupy partially inclined planes, so that the door closes and is maintained in its closed position by gravity, and that in supplying garbage to the receptacle when the door is open, the door may operate as a deflecting plate, preventing the garbage 90 from passing beyond the opening. Furthermore, such garbage as in the meantime may come to a position of rest on the inclined top section 6, is discharged therefrom by gravity, and that any portion of garbage possibly adhering to this surface is readily scraped therefrom by a shovel or other device. 95

The only object in having the bottom 4 projecting to the outer edge of the section 8 and curving the latter, as indicated at 19, is to provide a means for locating the garbage box 105 tight up against the wall or fence and so that the end of the discharge opening may be projected through and a comparatively small opening made therein for access from outside of such fence; as, for instance, into an alley. 110

In conclusion, it is to be observed that our invention provides for the construction of a garbage and refuse receptacle, the material, construction and weight of which compel its permanent location, complying with the sanitary laws for the health of a community, and from which it is surreptitiously removable, or removable at all, without destruction or serious injury, except when made in detachable sections in accordance with our invention and taken apart for the purposes of its removal from its original location. 115

While it is true that our invention provides for a garbage and refuse receptacle constructed in sections, adapted to be taken apart for its removal from one locality to another, after it has become an obstruction, from buildings or other causes, our invention broadly includes such a receptacle formed of fewer or a greater number of sections and also, when 120 125 130

molded as a whole from reinforced concrete or cement.

Having described our invention, what we claim and desire to secure by Letters Patent is:

In a garbage receptacle, a plurality of molded sections, certain of said sections hav-

ing aligned apertures molded therein, and rods passing through said apertures to maintain said sections in assembled position, certain of said sections resting upon said rods to be supported thereby. ¹⁰
